US0D1087328S

(12) **United States Design Patent** (10) **Patent No.:** **US D1,087,328 S**
(45) **Date of Patent:** **** Aug. 5, 2025**

(54) **FRAME SET**

(71) Applicant: **DCSTAR INC**, New York, NY (US)

(72) Inventor: **Ligui He**, New York, NY (US)

(73) Assignee: **DCSTAR INC**, New York, NY (US)

(**) Term: **15 Years**

(21) Appl. No.: **29/882,902**

(22) Filed: **Jan. 20, 2023**

(30) **Foreign Application Priority Data**

Jul. 27, 2022 (CN) 202230484551.5

(51) **LOC (15) Cl.** **29-02**

(52) **U.S. Cl.**

USPC **D24/110.1**

(58) **Field of Classification Search**

USPC D24/110.1, 108, 110-110.6, 162, 164;

(57) **CLAIM**

The ornamental design for a frame set, as shown and described.

DESCRIPTION

FIG. 1 is a front view of a frame set showing my new design;
FIG. 2 is a rear view thereof;
FIG. 3 is a left side view thereof;
FIG. 4 is a right side view thereof;
FIG. 5 is a bottom view thereof;
FIG. 6 is a top view thereof; and,
FIG. 7 is a perspective view thereof.

The broken lines depict portions of the frame set that form no part of the claimed design.

1 Claim, 7 Drawing Sheets
